(57) **CLAIM**

We claim the ornamental design for a shaving device, as shown and described.

DESCRIPTION

FIG. 1 is a front perspective view of a shaving device shown with the cap of the present invention showing my new design;

FIG. 2 is a front side elevation view thereof;

FIG. 3 is a back side elevation view thereof;

FIG. 4 is a side elevation view thereof;

FIG. 5 is another side elevation view thereof;

FIG. 6 is a top plan view thereof;

FIG. 7 is a bottom plan view thereof;

FIG. 8 is a perspective view of the shaving device shown without the cap;

FIG. 9 is a front side view of FIG. 8;

FIG. 10 is a back side view of FIG. 8;

FIG. 11 is a side view of FIG. 8;

FIG. 12 is another side view of FIG. 8;

FIG. 13 is a top plan view of FIG. 8; and,

FIG. 14 is a bottom plan view of FIG. 8.

The shaving device is shown with and without the cap for convenience of illustration.

The broken lines and unshaded areas therein illustrate portions of the shaving device that form no part of the claimed design.
